UNITED STATES PATENT OFFICE

2,453,993

CONNECTOR FOR BRACELETS, WRIST
WATCH STRAPS, ETC.Jacques Kreisler, New Rochelle, N. Y., assignor
to Jacques Kreisler Manufacturing Corpora-
tion, North Bergen, N. J.

Application March 16, 1945, Serial No. 583,156

6 Claims. (Cl. 24—233)

1

This invention relates to a connector or lock for bracelets, wrist watch straps, etc., or for other articles of jewelry or personal wear. The invention relates also to end-connecting members for bracelets, wrist watch straps, etc.

One object of the present invention is to provide a connector or lock with a plurality of locking members constructed and arranged to improve the securement of the releasable attachable part of the bracelet or other article provided with the connector and to facilitate the intended attachment or detachment of the attachable part to and from the connector.

Another object of the invention is the provision of a connector or lock having one or more locking members held by spring means in either locking or releasing position.

Another object of the invention is to provide a connector or lock with inner and outer locking members which have such predetermined relative positions in the releasing or retracted positions thereof that the attachable part of the article provided with the connector or lock can be easily applied to and removed from the connector.

Another object is to provide end-connecting members of improved construction for bracelets, wrist watch straps, etc., particularly end-connecting members which provide for the resilient expansion of the bracelet or strap on the wearer's wrist.

A yet further object of the invention is generally to provide a connector or lock of improved construction and operation, particularly with respect to the safety afforded by the connector or lock and with respect to facilitating the attachment and detachment of the attachable part to and from the connector by the wearer of the article provided with said connector or lock.

The above and other objects, features and advantages of the present invention will be fully understood from the following description, reference being had to the accompanying illustrative drawings.

In the drawings:

Fig. 1 is a front view of a connector embodying the present invention, said connector being shown attached to one end of a wrist watch strap having an attachable part at its opposite end;

Fig. 2 is an enlarged front view of the connector showing the attachable part in attached relation to the connector, a portion of said attachable part being cut away for the purpose of illustration;

Fig. 3 is a sectional view on the line 3—3 of Fig. 2;

2

Fig. 4 is a sectional view of the connector, the locking members being in their retracted positions;

Fig. 5 is a sectional view on the line 5—5 of Fig. 2;

Fig. 6 is an exploded perspective view of the several parts of the connector or lock embodying the present invention.

Referring now to the drawings in detail, there is shown in Fig. 1 a bracelet or wrist watch strap B provided with a connector or lock 10 embodying the present invention. The opposite ends of bracelet B are provided with the end-connecting members 12 and 14, respectively, which are of the same construction. One of these end-connecting members, here shown as member 12, is permanently secured to lock 10 while the other end-connecting member, here shown as member 14, is the attachable part which is releasably secured in the lock or connector 10.

Referring now more particularly to the construction of the connector or lock 10, the latter is formed of sheet metal or other suitable material and comprises a holding member 16 which is open at the top and has a bottom 18. Said bottom 18 is preferably curved longitudinally to conform to the wearer's wrist, the outer surface of said bottom being concave and the inner surface thereof being convex. Holding member 16 is provided with an end portion 20 which is curved or bent around and thereby secured to the cross bar 22 of the end-connecting member 12. Small lateral projections 24 are provided on bottom 18 adjacent the securing end portion 20 thereof in position to engage end-connecting member 12 for limiting the relative pivotal movement between said end-connecting member and the holding member 16 of the lock. The opposite end of holder 16 is provided with integral upwardly standing ears 26 having registering openings 28 for a pivot pin 30 which is secured therein. Inner and outer locking members 32 and 34, respectively, are pivotally mounted on pin 30, said inner and outer locking members being provided with apertured ears 36 and 38, respectively. Ears 36 of the inner locking member 32 are disposed at their inner sides of ears 26 of holding member 16, while ears 38 of the outer locking member are disposed at the outer sides of said ears 26. Outer locking member 34 is provided with a curved end or lip 40 which has a releasable snap engagement with the end 20 of holding member 16 for positively securing said outer locking member 34 in its projected or locked position. The inner locking member 32 is held releasably in its pro-

50
55

jected or locked position by engagement at its side edges with the inwardly bent upper portions 42 of the lugs 44 which are integral with and in upstanding relation to the bottom 18 of holding member 16. Outer locking member 34 is provided with an integral struck-out finger piece 45, and inner locking member 32 is provided with an integral finger piece 47 projecting from the free edge thereof.

It will be noted that the inner and outer locking members 32 and 34 are mounted for pivotal movement on a common pivot provided by the pivot pin 39 and that said locking members lie closely adjacent each other in the projected or locking positions of said locking members (Fig. 3) and in the retracted or releasing position of said locking members (Fig. 4). Thus, when the inner and outer locking members are in their retracted or releasing positions, the attachable part or end-connecting member 14 can be easily attached to and removed from the lock. More particularly as shown the end-connecting member 14 has a cross bar 46 which is spaced from a companion part 48 and defines therewith an opening 50 (Fig. 1) through which the inner and outer locking members 32 and 34 are movable for attaching and releasing the attachable part of end-connecting member 14 with respect to the lock. Cross bar 46 is positioned between ears 26 and lugs 44, as illustrated in Fig. 3, when received in holder 16 of the lock. Accordingly when the inner and outer locking members are in their projected or locking positions, bar 46 of the attachable part of end-connecting member 14 is securely held against unintended disengagement from holder 16 of the lock.

In accordance with the present invention provision is made for holding the inner and outer locking members in predetermined relation in the retracted or releasing positions thereof, illustrated in Fig. 4, whereby to facilitate the attachment and detachment of the attachable part of end-connecting member 14 with respect to lock 10. For this purpose holder 16 of the lock or connector is provided with spring means here shown as a flat spring 52 which is positioned on the bottom 18 of holder 16 at the inner side thereof. Flat spring 52 is curved longitudinally and lies in holder 16 with the convex curved surface abutting the inner convex curved surface of bottom 18. Spring 52 is secured in this position and relation by the engagement of the inner edge 54 of end portion 20 of the holder with the end portion 56 of the spring. Spring 52 is provided with cut outs 58 (Fig. 6) in its opposite side edges, and lugs 44 are positioned in said cut outs, thus preventing movement of spring 52 longitudinally and laterally of the holder 16. Longitudinally extending slits 60 disposed in laterally spaced relation are provided in the end portion of the spring which is positioned adjacent the pivot of the inner and outer locking members. These slits provide said last mentioned end portion of the spring with an intermediate flexible portion 62 and with lateral flexible portions 64 (Figs. 5 and 6). The ears or end portions 36 of the inner locking member 32 project transversely of the axis of its pivot on pin 39 have camming edges 66 which are engaged by the adjacent lateral spring portions 64, and the outer locking member 34 has a down turned end portion 68 which projects transversely of the axis of pivot pin 39 and is provided with an edge portion 70 of reduced width which is resiliently engaged by intermediate spring portion 62 in the locked po-

sition of outer locking member 34. In the retracted position of locking member 34 spring portion 62 engages the outer surface of portion 68. Spring portions 64 and 62 thus hold the inner and outer locking members in their projected and also in their retracted positions. It will be understood that when the locking members 32 and 34 are in their retracted or releasing positions, spring portions 62 and 64 hold the locking members against relative movement and in the adjacent relation illustrated in Fig. 4 so that the attachable part 14 can be easily applied to and removed from the lock or connector 10, while on the other hand, said spring portions oppose movement of the locking members from the closed or locking positions thereof to their unlocking positions and thus improve the safety characteristic of the lock. It will be noted that the outer locking member is movable to its retracted or unlocking position independently of the inner locking member and without impairment of the action of spring 52 in holding the inner locking member resiliently and releasably in its projected or locking position. On the other hand, the inner and outer locking members can be moved as a unit from their retracted positions to their locking or projected positions, that is from the positions illustrated in Fig. 4 to the positions illustrated in Fig. 3.

The end-connecting members 12 and 14 are preferably formed of sheet metal and are constructed to provide a desirable degree of expansion and contraction of the bracelet around the wearer's wrist, this being a desirable feature, particularly when the bracelet B itself which is provided with said end-connecting members is not elastic or expansible. Thus as here shown, the part 48 of the end-connecting member 14 is provided with a coiled compression spring 72 which is disposed within said part 48 and bears at one end thereof against the bent end 74 of part 48 and at its opposite end against the cross bar 76. Cross bars 46 and 76 are integral with side bars 78 and form a link 80. Part 48 is formed in one piece with an end portion 82 having apertured ears 84 which receive the ends of a pin 86 by which said part 82 is secured to the adjacent end of the bracelet B. The side bars 78 have integral guide portions 88 which project into the companion part through the open sides thereof to provide for the relative sliding of link 80 and the companion part 48. It will be understood that the end-connecting member 12 is of the same construction as the end-connecting member 14, as clearly illustrated in the drawings.

While I have shown and described the preferred embodiment of my invention, it will be understood that the latter may be embodied otherwise than as herein specifically illustrated or described and that in the embodiment of the invention herein disclosed, certain changes in the details of construction and in the arrangement of parts may be made without departing from the underlying idea or principles of the invention within the scope of the appended claims.

Having thus described my invention, what I claim and desire to secure by Letters Patent is:

1. In a lock of the class described comprising a holding member adapted to have an attachable part removably connected therein, inner and outer locking members pivotally connected to said holding member adjacent the same end thereof and movable from locking positions in which they both overlie said attachable part to prevent

disengagement thereof from said holding member, to retracted positions adjacent each other to permit engagement with or disengagement of said attachable part from said holding member, and spring means common to and simultaneously engageable with said locking members adjacent the pivots thereof for yieldingly holding said locking members in their locking and retracted positions, respectively.

2. In a lock of the class described comprising a holding member adapted to have an attachable part removably connected therein, inner and outer locking members pivotally connected to said holding member and co-axially turnable from locking positions in which they both overlie said attachable part to prevent disengagement thereof from said holding member, to retracted positions adjacent each other to permit engagement with or disengagement of said attachable part from said holding member, and spring means carried by said holding member and common to and simultaneously engageable with said locking members adjacent the pivots thereof for yieldingly holding said locking members in their locking and retracted positions, respectively.

3. In a lock of the class described comprising a holding member adapted to have an attachable part removably connected therein, inner and outer locking members pivotally connected to said holding member adjacent the same end thereof and turnable from locking positions in which they both overlie said attachable part to prevent disengagement thereof from said holding member to retracted positions adjacent each other to permit engagement with or disengagement of said attachable part from said holding member, said locking members having end portions adjacent the pivots of said locking members projecting transversely of the axis of said pivots, and spring means common to and simultaneously engaging said end portions for yieldingly holding said locking members independently of each other in their locking and projected positions, respectively.

4. In a lock of the class described comprising a holding member adapted to have an attachable part removably connected therein, inner and outer locking members pivotally connected to said holding member and turnable from locking positions in which they overlie said attachable part to prevent disengagement thereof from said holding member, to retracted positions to permit engagement with or disengagement of said attachable part from said holding member, said holding member having a bottom, and a flat spring member positioned on said bottom and secured to one end of said holding member, said flat spring member having an end portion movable toward and away from said bottom and directly engageable with said inner and outer locking members simultaneously adjacent the pivots thereof for yieldingly holding said locking members in their locking and retracted positions, respectively.

5. In a lock of the class described comprising a holding member adapted to have an attachable part removably connected therein, inner and outer locking members pivotally connected to said holding member adjacent the same end thereof and turnable from locking positions in which they overlie said attachable part to prevent disengagement thereof from said holding member, 70

to retracted positions to permit engagement with or disengagement of said attachable part from said holding member, said holding member having a bottom, and a flat spring member positioned on said bottom and secured to one end of said holding member, said flat spring member having an end portion movable toward and away from said bottom and directly engageable with said inner and outer locking members simultaneously

5 adjacent the pivots thereof for yieldingly holding said locking members in their locking and retracted positions, respectively, said end portion of the spring member having slits therein providing an intermediate part and lateral parts independently

10 flexible with respect to said intermediate part, said intermediate part engaging one of said locking members in said holding relation and said lateral parts engaging said other locking member in said holding relation.

15 6. In a lock of the class described comprising a holding member adapted to have an attachable part removably connected therein, inner and outer locking members pivotally connected to said holding member and turnable about a common pivoted axis from locking positions in which they

20 overlie said attachable part to prevent disengagement thereof from said holding member, to retracted positions to permit engagement with or disengagement of said attachable part from said holding member, said locking members having

25 adjacent their pivots end portions projecting transversely of the axis of said pivots, said holding member having a bottom, and a flat spring member positioned on said bottom and secured

30 to one end of said holding member, said flat spring member having an end portion movable toward and away from said bottom, said end portion of the spring member having slits therein providing an intermediate part and lateral parts independently

35 flexible with respect to said intermediate part, said intermediate and lateral parts of said spring member directly engaging said end portions, respectively, of said locking members for yieldingly holding said locking members, respectively, in either of said positions thereof.
